(57) CLAIM

The ornamental design for a modular component for use as a table top and bench seat, as shown and described.

DESCRIPTION

FIG. 1 is a perspective view of a modular component for use as a table top and bench seat showing my new design.

FIG. 2 is a front elevational view of the modular component of FIG. 1, the back elevational view being the mirror image thereof.

FIG. 3 is a right side elevational view of the modular component of FIG. 1, the left side elevational view being the mirror image thereof.

FIG. 4 is a top plan view of the modular component of FIG. 1.

FIG. 5 is a bottom plan view of the modular component of FIG. 1.

FIG. 6 is a perspective view of a modular component for use as a table top and bench seat showing a second embodiment of my new design.

FIG. 7 is a front elevational view of the modular component of FIG. 6, the back elevational view being the mirror image thereof.

FIG. 8 is a right side elevational view of the modular component of FIG. 6, the left side elevational view being the mirror image thereof.

FIG. 9 is a top plan view of the modular component of FIG. 6.

FIG. 10 is a bottom plan view of the modular component of FIG. 6.

FIG. 11 is a perspective view of a modular component for use as a table top and bench seat showing a third embodiment of my new design.

FIG. 12 is a front elevational view of the modular component of FIG. 11, the back elevational view being the mirror image thereof.

FIG. 13 is a right side elevational view of the modular component of FIG. 11, the left side elevational view being the mirror image thereof.

FIG. 14 is a top plan view of the modular component of FIG. 11.

FIG. 15 is a bottom plan view of the modular component of FIG. 11.

The modular component of the drawings shown with portions broken away indicate indeterminate lengths or widths. The broken line showing of legs in the figures is environmental only and forms no part of the claimed design.
